GUN FIRING SYSTEM

Arthur P. Davis, New York, and George Agins, Brooklyn, N. Y., assignors to Arma Corporation, Brooklyn, N. Y., a corporation of New York

Application August 25, 1944, Serial No. 551,135

12 Claims. (Cl. 89—41)

1

This invention relates to gun firing systems and has particular reference to an harmonic system for firing a gun from the rolling deck of a ship, at a predetermined point in the roll, and the present application is a continuation-in-part of application Serial No. 248,266, filed December 29, 1938.

In modern naval gun firing technique, the fire-control problem is solved for one chosen position in roll of the ship, generally the even keel position, and as the ship rolls through this position, the gun is fired by automatic contact mechanism of which the present invention is an improved form. Inasmuch as the gun is fired by electrical ignition of powder, best results are obtained when the total amount of heat generated by the firing current is constant, so that the firing contacts must be in engagement for a certain constant time determined by the characteristics of the gun, regardless of the speed of roll of the ship. A simple contact operated by the rolling of the ship is not adequate for this purpose, since the varying speed of roll of the ship would cause a varying contact period.

In accordance with the present invention, a gun firing system is provided in which the period of engagement of the firing contacts is constant, regardless of the speed of roll of the ship, so that a wide movement of a contact-engaging element in response to a roll does not result in a longer period of contact engagement than does a short movement thereof.

In a preferred embodiment of the invention, a pivoted contact-engaging lever, actuated in accordance with the roll of the ship, is weighted and balanced by a spring so that its natural period of oscillation is such that its time interval of swing is constant regardless of its amplitude. A contact carried or actuated by this lever cooperating with a second contact affording no restraint on the free swing of the lever, results in a contact engagement period which is a function of the inertia and resilience of the lever, and is unaffected by the amplitude of its swing. The harmonic lever thus makes use of the principle of resonance.

For a more complete understanding of the invention, reference may be had to the accompanying drawing, in which:

Figure 1 is a schematic showing of a typical form of a naval gun-firing contact-making switch embodying the present invention.

Fig. 2 is a curve graphically illustrating the relation between the face of the cam and the en-

2

gaged cam follower for one form of cam contour; and

Fig. 3 graphically illustrates the relation between the face of the cam and the engaged cam follower, for a different cam contour.

Referring to Fig. 1 of the drawing, numeral 10 designates the switch, whose contacting elements are connected in series in the gun firing circuit, not shown, and are adapted to be engaged by means of a cam 11 actuating a cam follower 12, in a manner to be described. Cam 11 is secured to gear 13 which meshes with gear 14 which is carried by the output shaft 15 of a mechanical differential 16. One input member of differential 16 is driven by gear 17 of a rotating shaft 18, which, for purposes of this invention, will be considered as the controlling element and may be actuated in accordance with the roll of the ship, such as by the level or cross-level angle mechanism of the gun director, as is determined by suitable instruments in accordance with usual practice. The other input member of the differential 16 is actuated by gear 19 mounted on shaft 20 and carrying a suitable dial 21 cooperating with a stationary index 22, so that the angular position of the shaft 20 may be read on dial 21. Handle 23 is provided on shaft 20 for changing the position of gear 13 and its attached cam 11 to any preselected angular position, as indicated on dial 21. While shaft 20 is illustrated as being manually operated by handle 23, it may be adjusted by suitable mechanism if desired. It will be observed that when handle 23 is at rest, gear 13 will be driven directly through differential 16 at an angular velocity which is proportional to the angular velocity of controlling element shaft 18, shaft 20 being locked by any suitable means, not shown, so that the lateral or side gears of the differential roll around the lower differential gear by controlling element 18 when shaft 20 is at rest.

A disc 62 of insulating material, about which gear 13 rotates, carries the switch 10 and cam follower 12 in such a way that the tip of follower 12 lies in position for cooperation with cam 11, being rigidly secured to the contact member 63 of the switch 10. Contact member 63 carries contact 65, insulated therefrom, and is pivotally mounted at 64 on disc 62. The cooperating contact member 68 of the switch 10 is mounted on the free end of spring 66 supported at its other end by post 67 on disc 62.

In the inoperative position of switch 10, with cam 11 disengaged from cam follower 12, a very small air gap is provided between cooperating

contacts 65 and 68, which are positioned in the firing circuit of the gun or guns in the given illustrative example, as indicated in Fig. 1. The external electrical connections to the switch 10 are made by means of suitable feed brushes and slip rings, not shown, but of conventional construction. A very light compression spring 58 resiliently holds contact member 63 normally disengaged from contact 68 and a stop pin 61 on disc 62 limits the movement of the member 63 by spring 58. Spring 58 exerts just enough pressure to keep the contact member 63 against stop 61 when the contact member 63 is in inoperative condition. Contact member 63 is weighted and balanced by spring 58 so that its natural period of oscillation is such that its time interval of swing is constant regardless of its amplitude.

Cam 11 is so positioned on gear 13 as to engage cam follower 12 when the rotation of gear 13 and counter rotation of disc 62 brings cam 11 and cam follower 12 into coincidence. The axis of the cam 11 is on a radius of gear 13 and its two faces 69 and 70 are identical, but reversed, so that the cam actuates follower 12 in the same way for both directions of rotation of the controlling element 18. The relationship between cam 11 and cam follower 12, when they are in engagement, is as illustrated in Fig. 2, and the faces of cam 11 are of the form $r=a-k\theta^2$, in polar coordinates, where a is the distance from the axis of rotation of gear 13 to the lowest point on the rising cam face. Therefore

$$\frac{dr}{dt} = -2k\theta \frac{d\theta}{dt}$$

Inasmuch as

$$\frac{d\theta}{dt} = v$$

it follows that

$$\frac{d^2r}{dt^2} = -2kv^2$$

which shows that the acceleration of the cam follower 12 is proportional to the angular velocity of the cam 11, and that the acceleration of the cam follower is constant for constant angular velocities of the cam, so that the wear on the cam faces and cam follower will be kept at a minimum value.

When the rotational path of the cam 11 is large compared to the size of the cam, a parabolic face cam may be used. The relationship between a parabolic cam and its cam follower is illustrated in Fig. 3, with the cam faces being of the form $y=cx^2$, in rectangular coordinates. Therefore

$$\frac{dy}{dt} = 2cx \frac{dx}{dt}$$

with the relative movement between cam 11 and cam follower 12 along the $x-x$ axis producing a displacement of cam follower 12 along the $y-y$ axis. The equation

$$\frac{dx}{dt} = v$$

is substantially correct, because the rotational path of cam 11 is large compared to the size of the cam, so that

$$\frac{d^2y}{dt^2} = 2v^2c$$

then shows that the acceleration of cam follower 12 along the $y-y$ axis is proportional to the velocity of cam 11 along the $x-x$ axis, and that the acceleration of the cam follower along the $y-y$ axis is constant for constant velocities of

movement of the cam. Accordingly, the wear on the cam faces and cam follower will be kept at a minimum value.

In the operation of the switch as illustrated in Fig. 1, a position of cam 11 with respect to cam follower 12 is selected by turning handle 23 until the desired position of the controlling element 18, at which the switch contact engagement should occur, is indicated by pointer 22 on dial 21. In the example given the position selected for cam 11 depends upon the gun fire delay which it is desired to compensate for, and the dial 21 may accordingly be graduated in units of time. Rotation of handle 23 effects rotation of gear 13 through shaft 20, gear 19, shaft 15 and connected gear 14, so that cam 11 will be turned to the pre-selected position. During this manual adjustment, the upper gear of the differential 16 is locked by gear 17 on controlling element 18.

Then, upon movement of the controlling element 18, the upper input member of differential 16 is rotated by gear 17 and as the lower gear of differential 16 is locked by gear 19, the differential output shaft 15 and gear 14 will rotate, so that gear 13 with its attached cam 11 revolves with an angular velocity corresponding to the velocity of the controlling element 18, which is proportional to the velocity of roll or pitch of the ship. By reason of the differential 16, the relative position of cam 11 may be changed during rotation of controlling element 18, by adjusting handle 23, the resultant movement being added to or subtracted from the driven movement of gear 13, as the case may be, so that the gun firing time may be adjusted relative to the roll and any desired fire delay compensation may be introduced.

When the cam 11 engages the cam follower 12 at constant velocity, the cam follower 12 will be moved by the face of the cam 11 at a constant acceleration, and when the cam follower 12 reaches the top of the cam 11, contact 65 will engage contact 68 to close the firing circuit of the gun or guns.

At the instant when the contacts 65 and 68 engage, the contact member 63 will have an angular momentum about pivot 64, and, as the comparatively considerable mass of the contact member 63 is constant its angular momentum will be proportional to its angular velocity. Contact spring 66 will therefore be deflected by the engagement of its contact 68 by contact 65 an amount which is proportional to the angular momentum of contact member 63. However, the period of time during which the contacts 65 and 68 are engaged will be constant under all conditions since it is independent of all factors except the mass of the lever 63 and the resiliency of cooperating spring 58 which form an harmonic system, as above described.

When the end of the initial half period of vibration of the aforementioned harmonic system is reached, contact 65, under the restoring force of spring 58, will disengage contact 68, and contact member 63 will return to its inoperative position against stop 61. The time during which the switch contacts 68 and 65 remain in engagement can be changed only by changing the constants of spring 66, or the mass of contact member 63.

Although a preferred embodiment of the invention has been illustrated and described herein, it is to be understood that the invention is not limited thereby, but is susceptible of changes in form and detail within the scope of the appended claims.

We claim:

1. In an harmonic system for firing a gun mounted on an unstable platform, the combination of relatively movable first and second members, means adapted for relatively moving said members in accordance with the movement of the platform, a swingable element on one of said members having a constant period of oscillation regardless of the amplitude of its oscillation and having an actuating portion, a contact carried by said element, a second contact resiliently mounted on said one member and in spaced relation to said first contact, a gun firing circuit including said contacts, and means on the other member for actuating said portion of said element to cause the element to engage its contact with said second contact at a predetermined point in the relative movement between said members and for a predetermined constant time interval independently of the velocity of the relative movement between said members.

2. In an harmonic system for firing a gun mounted on an unstable platform, the combination of relatively movable first and second members, means adapted for relatively moving said members in accordance with the movement of the platform, a swingable element on one of said members and having an actuating portion, a spring balancing the mass of said element to cause it to have a constant period of oscillation, regardless of the amplitude of its oscillation, a contact carried by said element, a second contact resiliently mounted on said one member and in spaced relation to said first contact, a gun firing circuit including said contacts, and means on the other member for actuating said portion of said element to cause the element to engage its contact with said second contact at a predetermined point in the relative movement between said members and for a predetermined constant time interval independently of the velocity of the relative movement between said members.

3. In an harmonic system for firing a gun mounted on an unstable platform, the combination of relatively movable first and second members, means adapted for relatively moving said members in accordance with the movement of the platform, a swingable element on one of said members having a constant period of oscillation regardless of the amplitude of its oscillation and having an actuating portion, a contact carried by said element, a second contact resiliently mounted on said one member and in spaced relation to said first contact, a gun firing circuit including said contacts, and cam on the other member for actuating said portion of said element to cause the element to engage its contact with said second contact at a predetermined point in the relative movement between said members and for a predetermined constant time interval independently of the velocity of the relative movement between said members.

4. In an harmonic system for firing a gun mounted on an unstable platform, the combination of relatively movable first and second members, means adapted for relatively moving said members in accordance with the movement of the platform, a swingable element on one of said members having a constant period of oscillation regardless of the amplitude of its oscillation, a contact carried thereby, a second contact resiliently mounted on said one member and in spaced relation to said first contact, a gun firing circuit including said contacts, a follower on said element, and means on the other member for actu-

ating said follower proportionally at the velocity of movement between said members to swing said element to cause it to engage its contact with said second contact at a predetermined point in the relative movement between said members and for a predetermined constant time interval independently of the velocity of the relative movement between said members.

5. In an harmonic system for firing a gun mounted on an unstable platform, the combination of relatively movable first and second members, means adapted for relatively moving said members in accordance with the movement of the platform, a swingable element pivoted on one of said members and having an actuating portion, a spring engaging said element for balancing the mass thereof to cause it to have a constant period of oscillation regardless of the amplitude of its oscillation, a contact carried by said element, a second contact resiliently mounted on said one member and in spaced relation to said first contact, a gun firing circuit including said contacts, and means on the other member for actuating said portion of said element to cause the element to engage its contact with said second contact at a predetermined point in the relative movement between said members and for a predetermined constant time interval independently of the velocity of the relative movement between said members.

6. In an harmonic system for firing a gun mounted on an unstable platform, the combination of relatively movable first and second members, means adapted for relatively moving said members in accordance with the movement of the platform, a swingable element on one of said members having a constant period of oscillation regardless of the amplitude of its oscillation and having an actuating portion, a contact carried by said element, a second contact resiliently mounted on said one member and in spaced relation to said first contact, a gun firing circuit including said contacts, and means on the other member for actuating said portion of said element to cause the element to engage its contact with said second contact at a predetermined point in the relative movement between said members and for a predetermined constant time interval independently of the velocity of the relative movement between said members.

7. In an harmonic system for firing a gun mounted on an unstable platform, the combination of relatively movable members, means adapted for relatively moving said members in accordance with the movements of the platform, a pair of contacts on one of said members, an harmonically oscillable lever on said one member for engaging said contacts and having an actuating portion, a cam on the other member for actuating said lever portion to cause the lever to oscillate and engage said contacts upon coincidence of the lever portion and cam during a predetermined position of said members in their relative movement, the contour of said cam effecting constant acceleration of said lever for constant relative velocity of said cam, whereby said harmonic oscillation of said lever causes the contacts to remain in engagement for a predetermined constant time interval after the lever has been actuated and independently of the velocity of the relative movement between said members.

8. In an harmonic system for firing a gun

mounted on an unstable platform, the combination of relatively moving members, means for relatively moving said members in accordance with the movements of the platform, a pair of contacts on one of said members, a lever on said one member having a constant period of oscillation for engaging said contacts and having an actuating portion, and a cam on the other member for actuating said lever portion to cause the lever to engage said contacts upon coincidence of the lever portion and cam during a predetermined position of said members in their relative movement, the contour of said cam effecting constant acceleration of said lever for constant relative velocity of said cam, whereby the oscillation of said lever causes the contacts to remain in engagement for a predetermined constant time interval after the lever has been actuated.

9. In an harmonic system for firing a gun mounted on an unstable platform, the combination of relatively moving members, means for moving one of said members relatively to the other member in accordance with the movement of the platform, a pair of contacts on one of said members, a lever pivoted on said one member and having a constant period of oscillation for engaging said contacts, an actuator for said lever, and a cam on said other member lying in the path of relative movement of said actuator for actuating said lever to effect engagement of said contacts at a predetermined point in the relative movement of said members, the contour of said cam effecting constant acceleration of said lever for constant relative velocity of said cam, whereby said oscillation of said lever causes said contacts to remain in engagement for a predetermined constant time independently of said velocity.

10. In an harmonic system for energizing the firing circuit of a gun mounted on an unstable platform, the combination of a member having a contact thereon located in said circuit, a lever pivoted on the member having a constant period of oscillation and having an actuating portion, a second contact on said member and located in said circuit, a second member relatively movable with respect to the first member, a cam thereon adapted to engage said lever portion during said relative movement to cause said lever to oscillate, means for relatively moving said members in accordance with the movement of said platform to cause said cam and lever portion to engage and close said contacts for a constant interval, and means for adjusting the relationship

40
45
50
55

8
between said members to vary the time of engagement between said cam and lever portion.

11. In an harmonic system for energizing the firing circuit of a gun mounted on an unstable platform, the combination of a member having a contact thereon located in said circuit, a lever pivoted on the member having a constant period of oscillation and having an actuating portion, a second contact on said member and located in said circuit, a second member relatively movable with respect to the first member, a cam thereon adapted to engage said lever portion during said relative movement to cause said lever to oscillate, means adapted for relatively moving said members in accordance with the movements of the platform to cause said cam and lever portion to cause said lever to engage and close said contacts for a constant interval, and means for adjusting the relationship between said members to vary the time of engagement between said cam and lever portion, said cam having a curvature such that said lever is moved thereby at constant acceleration for contact velocity of relative movement between said members.

12. In an harmonic system for energizing the firing circuit of a gun mounted on an unstable platform, the combination of a member having a contact thereon located in said circuit, a lever pivoted on the member having a constant period of oscillation and having an actuating portion, a second contact on said member and located in said circuit, a second member relatively movable with respect to the first member, a cam thereon adapted to engage said lever portion during said relative movement to cause said lever to oscillate, means for relatively moving said members relatively in accordance with the movements of the platform to cause said cam and lever portion to engage, and means for adjusting the relationship between said members to vary the time of engagement between said cam and lever, said cam having two operative surfaces for engaging said lever portion during opposite directions of movement between said members.
